COMBINATION GARMENT

Philip H. Robbins, New York, N. Y.

Application December 7, 1932, Serial No. 646,192

2 Claims. (Cl. 2—30)

This invention relates in general to garments and more particularly to a combination corset and brassière.

Garments including both corset and brassière have been devised before, it being customary in such garments to unite them either by stitching or by buttons or the like substantially all around the body. This arrangement, while forming a strong and durable construction, has certain very marked disadvantages to the wearer. It has been found for instance that when the wearer of such garment sits down or bends over, the rear of the garment, being attached directly to the shoulder straps or other supporting means, is pulled upwardly carrying the sides therewith. The corset of the garment, being more or less stiff, the entire corset will tend to slip upward on the body, thus placing it in an unnatural position. After the wearer straightens up, there is of course nothing to pull the corset and brassière back into natural position immediately, and it is necessary for the wearer to either allow same to remain in this unnatural position or to adjust it by hand. This is of course highly undesirable.

One of the principal objects of this invention is therefore to provide a garment, of the type described in which the corset and brassière will remain in proper position when the wearer bends over or sits down.

Another object of this invention is to provide a garment of the nature described in which the side and rear portions of the corset and brassière are allowed to separate upon bending of the wearer's body either in stooping over or in sitting down.

Another object of this invention is to provide a garment of the nature described in which the side and rear portions of the corset and brassière may move with respect to each other to allow the wearer to stoop or bend over or to sit down without displacing the corset portions, and in which these latter portions will be drawn back to normal position when the wearer straightens up again.

Another object of this invention is to provide a garment of the sort described in which the corset and brassière of the garment are allowed to move at the side and rear with respect to each other when the person stoops over or sits down, and in which they are automatically returned to their natural relation with respect to each other when the wearer straightens up.

Other objects and advantages of this invention will become apparent from the following description taken in connection with the accompanying drawing, and it is to be understood that

the same is by way of illustration and example only and is not to be taken as in any way limiting the spirit or scope of this invention. This invention is to be limited in its scope only by the prior art and by the terms of the appended claims.

Referring now to the drawing in which like numerals indicate corresponding parts throughout:

Figure 1 is a rear view of a garment embodying one form of this invention.

Figure 2 is a cross section taken along the line 2—2 of Figure 1.

As shown in the drawing, the garment embodying this invention consists in the main of a brassière indicated at 1 and a corset indicated at 2.

The brassière, as is the usual custom, is formed of some suitable fabric and is shaped to fit snugly about the body. It is provided also with shoulder straps 3 adapted to pass over the shoulders of the wearer and support the garment. These shoulder straps are preferably resilient and are attached to the upper binding or hem of the brassière by any convenient means such as stitching or the like.

The corset includes a front A, a back B and a pair of sides C. The central portion of the front is extended above the top of the sides and back. The front is formed of connected panels 6. The back consists of a single wide panel 3'. Each side is formed of a forward non-elastic panel 4, a rear non-elastic panel 4', a non-elastic intermediate panel 4'', an elastic intermediate panel 4''' and an elastic insert 5. The insert and panels of each side are connected together. The panels 4 of the sides are connected to front A. The panels 4' of the sides are connected to back B. The panel 4''' is interposed between panels 4 and 4''. The inserts 5 are arranged directly below panels 4 and between front A and panels 4'. The back B has its top edge designated 6'. The top edge of each side is designated 6'' and gradually rises from the ends of the edge 6' to the top edge of front A. The top edge of the latter includes a centrally disposed horizontal portion 12 and a pair of oppositely disposed outwardly curved outer edge portions 7' which depend from the ends of the edge portion 12 and merge into the forward ends of the top edges 6'' of the sides C at the panels 4. Projecting upwardly from the ends of the central edge portion 12 of the top of front A is a pair of spaced extensions 11' forming upward continuations of the curved edge portions 7'. The top edges of the back B and sides C are formed from a binder 11 in the form of a tape. The curved edge portions 7' and extensions 11' are formed from the binder

55

11. The edge portion 12 is formed from a binder 12' in the form of a tape. The inner sides of binder 11 are secured to the ends of binder 12'.

12. The forming of the top edge of front A with 5 the edge portions 7' and 12 provides the upper part of the front A of truncated tapered contour.

13. The brassière 1 has at its front a central portion 1' which closes the space formed between the 10 extensions 11' and edge portion 12. The lower edge of the front 9 of the brassière 1 is permanently secured to the edge portions 7' and 12 of the top edge of the front A of the corset. The 15 lower edges of the sides 9' and back 9'' of the brassière are not secured to, but depend below the top edges of the sides C and back B respectively 20 of the corset. The brassière 1 at its sides 9' and back 9'' opposes the outer faces of the sides C and back B of the corset. The brassière at its front extends outwardly with respect to the edge portions 7' at the top edge of the front A of the corset.

14. The panels 4'' correspond in height to that of each side of the corset. The inserts 5 are of less 25 height than panels 4''. The front A and back B of the corset are formed of non-elastic material.

15. The lower edge of the back 9'' of the brassière 1 is formed of a substantially horizontally disposed intermediate convex edge portion 10' and a pair of upwardly extending oppositely inclined 30 outer or side edge portions 10'' which merge into the lower edges 10''' of the sides 9' of the brassière. The length of the intermediate edge portion 10' of the lower edge of the back 9'' of the brassière is less than the width of the back of the 35 corset. Providing the back of the brassière with a lower edge of the form as stated forms said back with a lower part which gradually increases in width upwardly. Each side 9' of the brassière increases in height from its point of mergence 40 with the front 9 of the brassière to its point of mergence with the back 9'' of the latter. The brassière has its back portion of greater height than its front and side portions.

16. The upper ends of the straps 10 are anchored 45 at and inwardly adjacent to the points of mergence of the inclined edge portions 10'' with the horizontal edge portion 10' of the lower edge of the back of the brassière. The lower ends of the straps 10 are anchored at the points of connection 50 between the back B and sides C of the corset 2 and outwardly with respect to their upper ends.

17. Supporters 7 carried by elastic strips 8 are secured to the lower portion of the garment by means of stitching or the like, and serve to support 55 the stockings of the wearer and to assist in holding the corset part of the garment in proper position on the body.

18. In accordance with this invention, the bottom edge of the front of the brassière and top edge of 60 the front of the corset are firmly secured together across the front of the garment only by means of stitching or the equivalent, but this stitching is discontinued at the side portions and back portion of the brassière and the corset. The said 65 portions of the brassière are extended downwardly, as at 9', 9'', and overlap outside the upper edge of the sides and back portions of the corset all the way around the sides and back portions of the garment. This leaves the brassière and 70 corset of the garment free from each other across the sides and back of the wearer, and allows them to separate or at least to overlap to a smaller degree when the wearer bends over. This obviously eliminates the effect which has been spoken of in 75 connection with previous garments, namely the

moving upward of the corset and causing it to assume an abnormal position. The brassière has its side portions of greater height than and depending below the front portion thereof. The brassière has its back portion of greater height than the side and front portions thereof. The brassière has its back portion depending below the side portions thereof.

19. However, in order that the brassière and straps 3 which are secured thereto may serve to support 10 the rear portion of the corset as well as the front portion, this invention provides the employment of the pair of elastic or resilient bands 10 referred to. The lower ends of said straps or bands 10 are substantially in line with the respective shoulder straps and in such a position that they will just be tight without being stretched when the wearer is in upright position. When the wearer bends over however the bands 10 will stretch and will allow the brassière and the corset 20 to move relative to each other as above described, thus preventing the corset from being displaced, and further due to the point of connection of the bands with respect to the brassière and corset the bottom edge of the side and back portions of the 25 brassière will remain taut during the shifting of the corset and brassière relative to each other and when the garment is in normal position.

20. Provision is made at 13 for the garment to be opened down the side when putting it on or taking 30 it off. This opening is closed by any suitable well known means while the garment is being worn.

21. From the foregoing, it will be apparent that a garment of the type described has been provided in which are carried out all of the advantages and 35 objects of this invention.

22. A combination garment consisting of a corset and a brassière has been provided in which the two portions of the garment are held against separation from each other, and yet in which one of 40 the garments may move with respect to the other to accommodate the movement of the back of the wearer when she sits down or stoops over.

23. There has also been provided a garment consisting of a combined corset and brassière, in 45 which the wearer of the same may stoop over or sit down without such movement causing the corset to be pulled up and displaced from its normal position, but in which when the wearer straightens up again the brassière portion will be 50 pulled back to its normal position with respect to the corset.

24. What I claim is:—

25. 1. In a combination garment, a corset formed of front, sides and back portions, a brassière 55 formed of front, sides and back portions, the bottom of the front portion of the brassière being fixed throughout to the top of the front portion of the corset, the brassière having its sides and back portions of greater height than its front portion 60 and its back portion of greater height than the portions of the sides, said brassière having the portions of its sides and back free of connection throughout to the portions of the sides and back of the corset, said brassière having the portions 65 of its sides and back depending below the tops of and loosely encompassing the upper parts of the portions of the sides and back of the corset, said brassière having the bottom edge of its back portion formed with an intermediate part and a 70 pair of oppositely disposed upstanding outwardly inclined outer parts merging at their lower ends into the ends of said intermediate part and at their upper ends into the bottom edges of the brassière side portions, and a pair of spaced up- 75

standing oppositely inclined resilient straps having their upper ends anchored to the bottom edge of the back portion of the brassière inwardly adjacent to the point of mergence of said horizontal part with said inclined parts and having their lower ends anchored to the points of connection between the portions of the sides and back of the corset, said straps having their lower ends arranged outwardly adjacent with respect to their lower ends.

2. In a combination garment, a corset formed of front, sides and back portions, a brassière formed of front, sides and back portions, the bottom of the front portion of the brassière being fixed throughout to the top of the front portion of the corset, the brassière having its sides and back portions of greater height than its front portion and its back portion of greater height than the portions of its sides, said brassière having the portions of its sides and back free of connection

throughout to the portions of the sides and back of the corset, said brassière having the portions of its sides and back depending below the tops of and loosely encompassing the upper parts of the portions of the sides and back of the corset, said brassière having the bottom edge of its back portion formed with an intermediate part and a pair of oppositely disposed upstanding outwardly inclined outer parts merging at their lower ends into the ends of said intermediate part and at 10 their upper ends into the bottom edges of the brassière side portions, and a pair of spaced upstanding oppositely inclined resilient straps having their upper ends anchored at spaced points of and to the horizontal part of the bottom edge of 15 the back portion of the brassière and having their lower ends anchored to the corset, said straps having their lower ends arranged outwardly adjacent with respect to their upper ends.

PHILIP H. ROBBINS. 20
